UNITED STATES PATENT OFFICE
2,514,125
KNOCKDOWN CHAIR
George E. Evans, Collins, N. Y., assignor of one-half to C. Stuart Fielding, Buffalo, N. Y.
Application December 21, 1946, Serial No. 717,636
4 Claims. (Cl. 155—191)

1 This invention relates generally to improvements in chairs, but more particularly to an outdoor type of chair.

It has for one of its objects to provide a chair of this character which is so designed that it can be readily dismantled or knocked-down and compactly stacked for storage or shipment purposes, and which can be just as readily set up or assembled for use.

Another object of the invention is to provide a comfortable outdoor chair which is strong and rugged in construction and whose component parts are so organized and arranged as to effectively brace one another and afford ease and comfort to the user.

A further object is to provide a knock-down wooden chair which is simple and inexpensive in construction, which is light in weight, and which employs a minimum number of points of connection to require but a minimum of time in setting it up or knocking it down.

Other features of the invention reside in the construction and arrangement of parts herein-after described and particularly pointed out in the appended claims.

In the accompanying drawings:

Figure 1 is a side view of the chair embodying my invention. Figure 2 is a top plan view thereof. Figure 3 is a front elevation of the same. Figure 4 is a vertical section taken on line 4—4, Figure 2. Figure 5 is an enlarged side view of one of the chair arms and its associated parts. Figure 6 is a horizontal section taken on line 6—6, Figure 5.

Similar characters of reference indicate the corresponding parts throughout the several views.

In its general organization, my improved knock-down chair consists of a combined seat and leg-frame section 10, complementary, intersecting combined back-rest and leg-frame section 11, and a pair of arm-rest sections 12, the component sections 10, 11 being pivotally and detachably connected to each other at their point of intersection and the arm-rest sections being detachably or movably connected to the complementary leg-frame sections. Removably associated with the back-rest and leg-frame section 11 is a back-rest extension or head frame 13. These various sections are made of wood and when assembled for use assume the position shown in the drawings. When dismantled or knocked-down, the frame sections may be placed or stacked flatwise one upon another for convenient storage or shipment.

The seat and leg-frame section 10 is substantially rectangular in shape, including longitudi-

2 nal side bars 14, 14, transverse tie bars 15 and a series of transverse seat-forming bars 16. In the assembled position of the chair, this leg-frame section assumes the upwardly and forwardly-inclined position shown in Figures 1 and 4 with the rear end resting on the ground to provide a rear supporting leg and the front end elevated above the ground, while the complementary leg-frame section 11 assumes the upwardly and rearwardly inclined or reclined position shown and constitutes the front supporting leg of the chair. These complementary sections are detachably joined to each other at their point of intersection adjacent their respective front and lower ends by aligned removable dowel pins or bolts 17. The leg-frame section 11 is also substantially rectangular in shape, including longitudinal side bars 18 and transverse tie bars 19, the lower end thereof resting on the ground to provide a front supporting leg and spaced a considerable distance forwardly of the ground-engaging end of the complementary leg-frame to provide a firm and substantial footing or bearing for the chair. It will be noted that those tie bars immediately below the intersecting leg-frame section 10 also serve as shoulders or supports for such section, as seen in Figure 4.

Each arm-rest section 12 includes an arm-engaging portion 20 having a flange 21 depending substantially centrally therefrom and brace arms 22 joined at their upper ends thereto by bolts or dowel pins 23, 24 and detachably connected at their lower ends to the leg-frame section. These brace arms are disposed in parallel relation and inclined rearwardly, the front arm being connected at its lower end to the point of intersection of the leg-frame sections 10, 11 by the companion bolt 17 while the rear arm is connected at its lower end to the leg-frame section 10 by a bolt or dowel pin 25. Each bolt 24 also serves to detachably connect the arm rest with its companion rear brace arm 22 to the leg-frame section 11. By this construction, the arm rests and their companion brace arms also serve the further function of effectually retaining the intersecting leg-frame sections in their respective angular or inclined positions.

The detachable back-rest extension or head frame 13 is of lattice-like construction and overlies and is co-parallel with the upper portion of the leg-frame section 11 to provide a reclining back and head rest for the occupant of the chair. Its lower end 26 extends into a slot 27 formed in the rearmost seat-forming bar 16 of the leg-frame section 10 to retain it against fore and aft

as well as lateral displacement and is held against downward displacement by a transverse cleat 28 applied to the head frame 13 and adapted to abut against the top face of such bar, as shown in Figure 4. Adjacent its upper end this head frame is detachably connected to the leg-frame section 11 by bolts or dowel pins 29.

The chair can be painted in a variety of color schemes and the heads of the fastening pins or bolts may be painted in a contrasting color to render the chair neat and attractive in appearance.

When it is desired to knock-down the chair, the back-rest 13 is removed, and the bolts or dowel pins 17, 24, and 25 are removed to enable the leg-frame sections 10, 11 and the arm rest sections 12 to be disconnected from one another. These sections are then stacked on one another for compactness and when stored away require but a minimum of space. In assembling the chair, the leg-sections are brought into intersecting relation and then joined at their points of intersection, after which the arm-rest and back-rest sections are secured in their respective positions. In the knock-down and set-up operations, the leg-frame section 10 is slid out of or into intersecting relation with the complementary leg-frame section 11. While manifestly simple, compact and inexpensive in construction, this chair is light in weight, attractive and comfortable and can be readily set-up and knocked-down.

I claim as my invention:

1. A chair of the character described, comprising a pair of complementary leg-frame sections disposed in intersecting connected relation and providing spaced leg supports at their lower ends, one frame section having a seat portion forwardly of the plane of intersection of the sections and the companion section having a back portion extending above the plane of intersection, and arm rests projecting forwardly from that section having the back portion and each having parallel brace members depending therefrom with one connected to the point of intersection of said sections and the other to the seat-bearing leg frame to the rear of the plane of intersection of the sections.

2. A chair of the character described, comprising a combined seat and leg-frame section, a complementary intersecting, combined back-rest and leg-frame sections connected thereto at the point of intersection of the sections, the first-named section being inclined upwardly and forwardly and constituting a rear supporting leg and the complementary section being inclined upwardly and rearwardly and constituting a front supporting leg, and arm-rest sections connected to said complementary leg-frame section and having brace arms depending therefrom and joined, respectively, at their lower ends to the point of in-

tersection of said sections and to the seat frame section at a point rearwardly of the intersecting plane of said sections.

3. A chair of the character described, comprising a combined seat and leg-frame sections, a complementary intersecting, combined back-rest and leg-frame sections connected thereto at the point of intersection of the sections, the first-named section being inclined upwardly and forwardly and constituting a rear supporting leg and the complementary section being inclined upwardly and rearwardly and constituting a front supporting leg, and arm-rest sections extending forwardly from and detachably connected at their rear ends to the opposite sides of said complementary leg-frame sections and each having a pair of brace arms depending therefrom, one arm of each pair being detachably connected to the leg-frame sections at their point of intersection and the other arm of each pair being detachably connected to the combined seat and leg-frame section at a point spaced to the rear of the intersecting point of such sections.

4. A chair of the character described, comprising a pair of substantially rectangular-shaped frames adapted to be detachably joined in intersecting relation with one frame extending upwardly and forwardly to provide a rear supporting leg and the companion frame extending upwardly and rearwardly to provide a front supporting leg, the front portion of the first-named frame extending forwardly beyond the companion frame and constituting a seat and the upper portion of such companion frame constituting a reclining back for the chair, and arm rest sections extending forwardly from the front leg frame section above the plane of the rear leg frame section and including front and rear brace members pending therefrom and detachably connected to said frames, the front brace members being detachably jointed at their lower ends to the intersecting points of connection of said frames and the rear brace members being connected at their lower ends to the rear leg frame section to the rear of its point of connection to the companion leg frame section.

GEORGE E. EVANS.
